(57) **CLAIM**

The ornamental design for an electrolytic plating anode, as shown and described.

DESCRIPTION

The claimed electrolytic plating anode is used to perform an electrolytic plating process in a plating bath when a voltage is applied via an anode shaft connected to the electrolytic plating anode.

FIG. 1 is a front elevation view of an electrolytic plating anode;

FIG. 2 is a rear view of the electrolytic plating anode shown in FIG. 1;

FIG. 3 is a top plan view of the electrolytic plating anode shown in FIG. 1, wherein the broken lines form no part of the claimed design;

FIG. 4 is a bottom plan view of the electrolytic plating anode shown in FIG. 1;

FIG. 5 is a right side view of the electrolytic plating anode shown in FIG. 1; and,

FIG. 6 is a left side view of the electrolytic plating anode shown in FIG. 1.

1 Claim, 6 Drawing Sheets
